ARTHUR R. SCHWARZKOPF, OF CHICAGO, ILLINOIS, ASSIGNEE TO THEO. A. KOCHS COMPANY, OF CHICAGO, ILLINOIS, A CORPORATION OF ILLINOIS

BARBER'S CHAIR

Application filed July 8, 1929. Serial No. 376,684.

This invention relates to barbers' chairs, and has reference more particularly to the backs of chairs, such as barbers' and dentists' chairs, and the like, and its principal object is to provide novel means for guiding the head rest slide and holding it in its various positions of adjustment. Another object is to provide novel means for fastening the slide guiding means to the framework of the chair back. Another object is to provide simple and efficient means for securing together the wooden framework of the chair back and the marginal metal frame member thereof.

With these and other objects and advantages in view, this invention consists in the several novel features of construction, arrangement and combinations of parts herein-after fully set forth and claimed.

The invention is clearly illustrated in the drawing accompanying this specification in which—

Figure 1 is a rear elevation of a fragment of a chair back embodying a simple form of the present invention;

Fig. 2 is a detail central vertical cross section taken on the line 2—2 of Fig. 1;

Fig. 3 is a detail vertical longitudinal section taken on the line 3—3 of Fig. 2;

Fig. 4 is a detail horizontal section taken on the line 4—4 of Fig. 3;

Fig. 5 is a side elevation of a fragment of the marginal frame member looking in the direction of the arrow 5 in Fig. 2; and

Fig. 6 is a perspective view of a collar employed for securing the upper end of the marginal frame member to the wooden framework of the chair back.

Referring to said drawing, the reference characters, 6, 6^a, 7 and 7^a designate horizontal and vertical frame members which comprise the framework of the chair back. These members are preferably formed of wood, glued and otherwise rigidly secured together as by dowel pins to form a strong and substantial framework.

A marginal frame member 8, preferably formed of enameled metal ware surrounds the framework of the back, and its lower end is secured thereto in any suitable manner, as, for instance, by screws 8^a which enter the

wooden framework from below. A metallic sheet, or other suitable sheet of material, 9 is rigidly held between the framework and marginal frame member 8. The marginal frame member 8 preferably comprises a structure, angle shaped in cross section, having a flange 10 which overlies the back sheet 9 and a flange 11 which overlies the edge portion of the framework.

A slide or slide bar 12 for the head rest (not shown) is provided, as usual, and said slide enters a vertical groove 7^b formed in the members, 6, 6^a and 7 of the wooden framework through a slot or opening 13 in the upper horizontal flange 11 of the marginal frame member 8. A guide member 14 is provided for guiding the slide 12 in the chair back, and said guide member is formed with a vertical guideway or channel 15 (see Figs. 3 and 4) in which the slide is slidably guided.

The guide member 14 is contained in the vertical groove 7^b, as seen in Figs. 3 and 4, and is rigidly secured to the framework by screws 16 which pass through the wooden framework and are threaded in plates or bars 17 which act as nuts and are secured to the opposite side of the wooden framework by screws 17^a. The bars or plates 17^a have tapped holes for the reception of the screws 16, and being rigidly fastened to the wooden framework, they will not drop into the upholstery when the screws 16 are unscrewed therefrom, as would be the case were ordinary nuts employed on the ends of the screws.

Should occasion require the removal of the guide member 14, this may be conveniently done without any danger of the nuts becoming displaced. In order to obtain access to the heads of the screws, the wall 18^a of the guide member is formed with apertures 19 arranged in alignment with the axes of the screws 16, as is clearly illustrated in Figs. 3 and 4.

A rectangular collar 20 is employed for rigidly holding the upper end of the marginal frame member 8 in place on the wooden framework. Said collar has a rectangular opening 20^a therethrough for the passage of the slide 12 and it is formed with downwardly projecting flanges 20^b which enter the open-

ing 13 in the marginal frame member 8. It is also formed with a marginal top plate 20^c that lies upon the upper face of the marginal frame member 8 and completely covers the opening 13 with the exception of the slot for the slide 12. The rectangular sleeve is provided with screw holes for the reception of screws 21 which are threadedly engaged in laterally extending ears 18^c formed at the upper end of the guide member 14. Above the ears 18^c, the guide member 14 is formed with a neck portion 18^d that enters a socket in the collar formed between the side flanges 20^b thereof.

15 In assembling the marginal frame member 8 with the wooden framework, the neck portion 18^d of the guide member 14 is inserted into the opening 13 of the marginal frame member and the lower end of the marginal frame member is then swung against the wooden framework and its lower end secured in place with the screws 8^a. Thereafter, the flanges 20^b of the collar 20 are inserted through the opening 13 in the marginal frame member, the neck portion 18^d of the guide member 14 entering the socket in the collar 20, after which the screws 21 are inserted and screwed down, thereby rigidly connecting the collar with the guide member.

20 It is to be observed that a rigid connection is obtained between the wooden framework and the marginal frame member 8 which takes all of the strain off the screws 21, inasmuch as the neck portion 18^d of the guide member 14 fits fairly tight in the socket of the collar 20, and the flanges of the collar fit fairly tight in the slot or opening 13 of the marginal frame member 8.

25 The slide 12 is formed with teeth 22 on one side, which teeth co-operate with a latch in the form of a dog or pawl 23, whereby the slide may be held in any vertical position of adjustment. The dog 23 is pivotally connected to the guide member 14 by a pin 24 which is secured in ears 25 formed on the wall 18^a of the guide member. The upper end of the dog passes through a slot in the wall 18^a of the guide member and is yieldingly held in engagement with a tooth of the slide by a spring 26 interposed between the wall 18^a and an arm 27 of the dog.

30 It will be observed that by depressing said arm 27 of the dog, the latter will be disengaged from the slide 12 whereupon the same may be lowered to any position of adjustment, and when the dog is released, it will engage with the adjacent tooth and support the slide in such adjusted position. The teeth of the slide are preferably in the form of ratchet teeth, as shown, whereby the slide may be withdrawn by merely pulling the same out of the chair back.

35 A push button 28 is provided for actuating the pawl or dog 23, and said push button is held in an aperture contained in a depending

lug 29 which is formed upon the marginal frame member 8. The push button is located behind the arm 27 of the dog 23 in position to engage the same when pressed inwardly, and a spiral spring 30 is provided for returning the push button to its normal position. As shown, the push button is slightly tapered and when pushed outwardly by the spring 30, seats against the tapered wall of the aperture in which it is contained.

40 On the rear side of the lug 29 is formed a U-shaped socket member 31 partially surrounding the rear end of the push button and serving as an abutment for one end of the spiral spring 30 which surrounds a reduced part of the push button. The other end of the spiral spring 30 bears against a shouldered part of the push button. The latter may be inserted into the aperture in the lug 29 from the rear thereof, after which the spiral spring may be inserted into the socket 31 through the upper open end thereof, the smaller convolution of the spring being placed over the smaller end of the push button. From this it will be observed that the spring actuated push button is separately mounted in the marginal frame member 8, whereas the dog or pawl is mounted on the guide member 14. This arrangement enables the guide member, together with the dog or pawl, to be assembled with the framework of the chair back, after which the sheet backing 9 and marginal frame member 8 with the push button 28 contained therein may be secured to the framework in assembling the parts. The framework may be upholstered in the usual manner, a fragment of which is seen at 32.

45 I claim:

1. In a chair, the combination with the wooden framework of a chair back, said framework having a vertical groove in one side thereof, of a guide member contained within said groove and having integrally formed side walls and end walls defining a longitudinally extending enclosed guideway for a head rest slide, screws extending through the side wall of said guide member behind said guideway and through said framework, and tapped members for holding said screws, said tapped members being positioned against the opposite side of and rigidly fastened to said wooden framework, whereby to provide an anchor for the screws and strengthen the frame adjacent the groove.

50 2. In a chair, the combination with the framework of a chair back, said framework having a vertical groove in one side thereof, of a guide member contained within said groove and having integrally formed side and end walls defining a longitudinally extending enclosed guideway for a head rest slide, screws extending through the side wall of said guide member behind the guideway therein and through said framework, and

5 plates positioned against the opposite side of said framework and secured thereto and having tapped holes for the reception of said screws, whereby to provide an anchor for the screws and strengthen the frame adjacent the groove.

10 3. In a chair, the combination with the framework of a chair back and a marginal frame member of angle formation surrounding the edge portions thereof and fastened to the bottom of the framework by screws, said frame member having a slot in its upper end, of a guide member secured to said framework and having a longitudinally extending channel therein for the reception of a head rest slide, and a collar covering the slot in said marginal frame member and forming an interlocking connection between said marginal frame member and said guide member, said 15 collar being secured to said guide member by screws.

20 4. In a chair, the combination with the framework of a chair back and a slotted marginal frame member of angle formation surrounding the edge portions thereof, there being fastening means at the lower end of the marginal frame member for securing it to the framework, of a guide member secured to said framework and having a longitudinally extending channel therein for the reception of the head rest slide, said guide member having a neck portion extending into the slot of the marginal frame member, and a collar overlying the slot in the marginal 25 frame member and having downwardly projecting flanges entering the space between the walls of said slot and the neck portion of the guide member, said collar being screwed to said guide member.

30 5. In a chair, the combination with the framework of a chair back and a marginal frame member surrounding the edge portions thereof and having an opening in its upper end, of a guide member secured to said framework and having a longitudinally extending channel therein for the reception of a head rest slide and having a neck portion extending into said opening, a collar having a plate exterior of the marginal frame member and flanges extending into the opening of the marginal frame member with the neck portion of the guide member contained in a socket between said flanges, and screws connecting said collar with said guide member.

35 6. In a chair, the combination with the framework of a chair back and a marginal frame member of angle formation surrounding the edge portions thereof, said marginal frame member being formed with a slot in its upper end, of a guide member secured to said framework and having a longitudinally extending channel therein for the reception of a head rest slide, said guide member being formed with a neck portion entering the slot in the marginal frame member, a collar over-

lying the slot in the marginal frame member and having a socketed portion entering the space between the walls of the slot and the neck portion of the side member, and fastening members for securing the collar and guide 70 member together.

7. In a chair, the combination with the framework of a chair back, of a guide member for a head rest slide secured thereto, said guide member having a vertically extending channel formed therein, a toothed slide guided in said channel, a spring pressed dog fulcrumed upon said guide member and engaging with the teeth of the slide, a marginal frame member removably secured to said framework, a socket member carried by said marginal frame and a spring pressed push button independently carried by said socket member and projecting from opposite sides 80 of said marginal frame, whereby to be pushed 85 against said dog.

8. In a chair, the combination with the framework of a chair back and a marginal frame member removably secured thereto, of a guide member for a head rest slide separate 90 from the marginal frame and secured to the framework of the chair back, a toothed head rest slide guided in said guide member, a spring pressed dog fulcrumed upon said guide member and engaging with the teeth 95 of the slide, and a spring pressed dog engaging push button mounted in said marginal frame member, there being clearance space between said push button and the dog.

9. In a chair, the combination with the framework of a chair back and a marginal frame member removably secured thereto, of a guide member separately secured to said framework and having a longitudinally extending channel, a head rest slide guided in said channel, a spring pressed dog fulcrumed upon said guide member and arranged to supportingly engage said slide at a plurality of places thereon, said marginal frame having a socket and a tapered opening communicating therewith, and a push button contained in the socket and normally seated in the tapered opening in the marginal frame member in alignment with an arm of said dog whereby the latter may be actuated to disengage the same from the slide, said marginal frame member together with the push button being removable and replaceable independently of the guide member and dog. 100 105 110 115

10. In a chair, the combination with the framework of a chair back and a marginal frame member removably secured thereto, of a guide member separately secured to the framework and having a longitudinally extending channel therein, a head rest slide guided in said channel, a spring pressed dog fulcrumed upon said guide member and arranged to supportingly engage said guide 120 at a plurality of places thereon, and an outwardly and independently spring pressed 125 130

push button contained in said marginal frame member in alignment with an arm of said dog whereby the latter may be disengaged from said slide, said marginal frame member together with the push button being removable and replaceable independently of the guide member and dog.

- 5 11. In a chair, the combination with the framework of a chair back and a marginal frame member surrounding the edge portions thereof, of a guide member secured to said framework and having a longitudinally extending channel therein for the reception of a head rest slide, said marginal frame member having an opening in line with the channel of the guide member, a slotted plate over the slot in said marginal frame member, and screws extending through said slotted plate into the guide member.
- 10 12. In a chair, the combination with the framework of a chair back, a guide member for a head rest slide secured thereon and a slide supporting dog fulcrumed on said guide member, of a marginal frame member surrounding the edge portion of the framework and removably mounted thereon, said marginal frame member having a button receiving aperture formed therein in alignment with an arm of said dog, and said marginal frame member being formed with a spring retaining socket around said aperture, a push button in said aperture, and a spring contained in said socket and engaging said push button.
- 15 30 35 In witness whereof, I have hereunto set my hand this 29th day of June, 1929.

ARTHUR R. SCHWARZKOPF.
